(57) **CLAIM**

The ornamental design for a combination ceiling fan and light fixture, as shown and described.

DESCRIPTION

FIG. 1 is a perspective view from below of a combination ceiling fan and light fixture in accordance with my design;

FIG. 2 is a greatly reduced top plan view of the combination ceiling fan and light fixture in accordance with my design;

FIG. 3 is a reduced bottom plan view of the combination ceiling fan and light fixture in accordance with my design;

FIG. 4 is a front elevation view of the combination ceiling fan and light fixture in accordance with my design;

FIG. 5 is a back elevation view of the combination ceiling fan and light fixture in accordance with my design; and,

FIG. 6 is a side elevation view of the combination ceiling fan and light fixture in accordance with my design, the opposite side being a mirror image of that shown.

The broken lines showing environmental structure are for illustrative purposes and form no part of the claimed design.

The broken line showing of the canopy is included for the purpose of illustrating environmental structure and forms no part of the claimed design.
